7-ALKYLMERCAPTOACETAMIDO
CEPHALOSPORINS

This invention relates to cephalosporin compounds which have antibacterial activity. In particular, the invention relates to compounds possessing an alkylmercaptoacetamido substituent at position 7 of the cephem nucleus and an S-hetero substituent at position 3.

The compounds of this invention are represented by the following structure:

in which:

R is lower alkyl of one to six carbon atoms;

M is hydrogen or an alkali metal or ammonium cation; and

A is CH_2SHet , where Het is a five or six membered heterocyclic ring containing two to four atoms selected

However, no 7-alkylmercaptoacetamido cephalosporins incorporating a 3-S-heterocycle have been disclosed.

The compounds of this invention are prepared by acylation of an aqueous solution of the sodium salt of the appropriate 7-aminocephalosporanic acid nucleus, where A = CH_2SHet , with an appropriately substituted alkylmercapto-acetic acid chloride.

The 7-aminocephalosporin nuclei where A = CH_2SHet are prepared by known methods from 7-aminocephalosporanic acid (7-ACA) and the appropriate heterocyclic mercaptan compound.

The cephalosporins of this invention possess antibacterial activity. They are active against both Gram-positive and Gram-negative organisms. Minimum inhibitory concentrations (MIC) ranged from 0.2 to >200 ug./ml. in in vitro testing. Upon in vivo subcutaneous administration the compounds also show significant activity. These results are summarized in Tables I and II; structures of the compounds appear in Table III.

The compounds are formulated and administered by injection in the same manner as other cephalosporins with the dose depending on the subject and infection being treated.

from the group consisting of N, O and S, unsubstituted or substituted with from one to two groups selected from lower alkyl, alkoxyalkyl or trifluoromethyl, each alkyl or alkoxy having from one to four carbon atoms.

Preferred compounds are those where Het is unsubstituted or methyl substituted triazolyl, tetrazolyl, oxazolyl, oxadiazolyl, thiazolyl or thiadiazolyl. Also preferred are compounds where R is methyl, ethyl or propyl.

Included within the scope of this invention are the pharmaceutically acceptable salts that are formed by reaction of the cephalosporanic acid with a pharmaceutically acceptable base.

Preparation of various 7-alkylmercaptoacetamidocephalosporanic acid derivatives is described, inter alia, in British Pat. No. 1,038,529 (1966) and U.S. Pat. Nos. 3,270,012 (1966) and 3,297,692 (1967). British Pat. No. 1,038,529 discloses such compounds with a pyridiniummethyl, imidazoliummethyl, or methylimidazoliummethyl substituent at the 3-position, U.S. Pat. No. 3,297,692 discloses such compounds with a 3-acetoxymethyl group. U.S. Pat. No. 3,270,012 discloses generically 3-pyridiniummethyl compounds.

09626	methyl	4-methyl-1,2,4-triazol-5-ylthiomethyl

The following examples illustrate the invention but are not to be construed as limiting the scope thereof. Temperatures are in degrees Centigrade unless otherwise stated.

EXAMPLE 1

7-Amino-3-(1-methyl-1,2,3,4-tetrazol-5-ylthiomethyl)- Δ^3 -cephem-4-carboxylic acid

To a suspension of 27.2 g. (0.1 mol.) of 7-ACA in 200 ml. of water and 100 ml. of acetone was added a solution of 18.9 g. of sodium bicarbonate in 200 ml. of water. The resultant solution was warmed on a steam bath and a solution of 14.5 g. (0.125 mol.) of 1-methyl-5-mercaptop-1,2,3,4-tetrazole in 200 ml. of acetone was added. The reaction mixture was refluxed for 3.5 hr. while maintaining the pH at 7.4-8.0 by addition of 5 percent sodium bicarbonate. Acidification of the cooled reaction mixture to pH 3.5 with 6N hydrochloric acid resulted in precipitation of 7-amino-3-(1-methyl-1,2,3,4-tetrazol-5-ylthiomethyl)- Δ^3 -cephem-4-carboxylic acid which was collected, washed with water and air-dried (16 g.; 49 percent).

EXAMPLE 2

7-Methylmercaptoacetamido-3-(1-methyl-1,2,3,4-tetrazol-5-ylthiomethyl)- Δ^3 -cephem-4-carboxylic acid

To a stirred, cooled (-20°) solution of 8.50 g. (0.026 mol.) of 7-amino-3-(1-methyl-1,2,3,4-tetrazol-5-ylthiomethyl)- Δ^3 -cephem-4-carboxylic acid in 220 ml. of 3 percent sodium bicarbonate and 220 ml. of acetone was dropwise added a solution of 3.66 g. (0.029 mol.) of methylmercaptoacetyl chloride in 52 ml. of acetone, during which time the pH of the reaction mixture was maintained at 8.0 by addition of 10 percent sodium hydroxide. After addition the reaction mixture was stirred an additional 20 minutes at -15° then was warmed to room temperature and extracted with ether. The remaining aqueous phase was cooled, 250 ml. of ethyl acetate was added and the slurry was acidified to pH 3.5 with 3N hydrochloric acid. The layers were separated and the aqueous phase was extracted twice more with ethyl acetate. The combined extracts were dried ($MgSO_4$) and concentrated in vacuo to yield 6.8 g. of a gummy solid that was chromatographed on 300 g. of silica gel with $CHCl_3:iPrOH:HCO_2H$ (90:10:3) to yield 4.6 g. (43 percent) of 7-methylmercaptoacetamido-3-(1-methyl-1,2,3,4-tetrazol-5-ylthiomethyl)- Δ^3 -cephem-4-carboxylic acid. Conversion to the corresponding sodium salt was accomplished by addition of 2.6 ml. of a 30 percent solution of sodium 2-ethylhexanoate in isopropanol to a solution of 2.0 g. of the free acid in 20 ml. of methanol. Ether (100 ml.) was added to precipitate the salt which was collected, washed with ether and dried in vacuo.

EXAMPLE 3

7-Ethylmercaptoacetamido-3-(1-methyl-1,2,3,4-tetrazol-5-ylthiomethyl)- Δ^3 -cephem-4-carboxylic acid

The procedure as described in Example 2 was followed utilizing 2.95 g. (0.009 mol.) of 7-amino-3-(1-methyl-1,2,3,4-tetrazol-5-ylthiomethyl)- Δ^3 -cephem-4-carboxylic acid in 60 ml. of 3 percent sodium bicarbonate and 60 ml. of acetone and 1.38 g. (0.010 mol.) of ethylmercaptoacetyl chloride in 20 ml. of acetone. The acidified (pH 2.8) aqueous solution was extracted with ethyl acetate and the combined extracts were washed (H_2O), dried ($MgSO_4$) and concentrated in vacuo to yield 2.38 g. (62 percent) of 7-ethylmercaptoacetamido-3-(1-methyl-1,2,3,4-tetrazol-5-ylthiomethyl)- Δ^3 -cephem-4-carboxylic acid. The free acid (2.3 g.) was dissolved in 50 ml. of ethyl acetate and 3.06 ml. of a 30 percent solution of sodium 2-ethylhexanoate in isopropanol was added. The solution was filtered and 200 ml. of ether was added to the filtrate to precipitate the salt which was collected, washed with ether and dried in vacuo. Recrystallization from methanol afforded 1.39 g. of the pure salt.

EXAMPLE 4

7-n-Propylmercaptoacetamido-3-(1-methyl-1,2,3,4-tetrazol-5-ylthiomethyl)- Δ^3 -cephem-4-carboxylic acid

To a stirred, cooled ($-10^\circ C.$) solution of 3.28 g. (0.010 mol.) of 7-amino-3-(1-methyl-1,2,3,4-tetrazol-5-ylthiomethyl)- Δ^3 -cephem-4-carboxylic acid in 62.5 ml. of 3 percent sodium bicarbonate and 62.5 ml. of acetone was added dropwise a solution of 1.84 g. (0.012 mol.) of n-propylmercaptoacetyl chloride in 20 ml. of acetone, during which time the pH of the reaction mixture was maintained at 7.6-8.0 with 10 percent sodium hydroxide. After addition the reaction mixture was stirred an additional 20 minutes in the cold, then it was warmed to room temperature, diluted with 100 ml. of water, and extracted with ether. Ethyl acetate (150 ml.) was added to the aqueous phase which was then acidified to pH 2.5 with 3N hydrochloric acid. The layers were separated and the aqueous phase was again extracted with ethyl acetate. The combined extracts were washed (H_2O), dried ($MgSO_4$) and concentrated in vacuo to give 3.0 g. (67 percent) of a yellow foam identified as 7-n-propylmercaptoacetamido-3-(1-methyl-1,2,3,4-tetrazol-5-ylthiomethyl)- Δ^3 -cephem-4-carboxylic acid. The crude acid (3.0 g.) was dissolved in 25 ml. of ethyl acetate and 25 ml. of acetone to which was added a 30 percent solution of sodium 2-ethylhexanoate to pH 6.3. The precipitated sodium salt was collected, washed with ether and dried in vacuo. Addition of ether to the filtrate caused additional amounts of salt to precipitate which were combined with the first crop and recrystallized from methanol-ether to give 1.27 g. of pure salt.

N	17.34	16.96

EXAMPLE 5

7-Amino-3-(4-methyl-1,2,4-triazol-3-ylthiomethyl)- Δ^3 -cephem-4-carboxylic acid

The title compound was obtained from reaction of 7-ACA and 4-methyl-3-mercaptop-1,2,4-triazole by the same procedure as described in Example 1.

EXAMPLE 6

7-Methylmercaptopacetamido-3-(4-methyl-1,2,4-triazol-3-ylthiomethyl)- Δ^3 -cephem-4-carboxylic acid

The procedure as described in Example 2 was followed utilizing 3.92 g. (0.013 mol.) of 7-amino-3-(4-methyl-1,2,4-triazol-3-ylthiomethyl)- Δ^3 -cephem-4-carboxylic acid in 80 ml. of 3 percent sodium bicarbonate and 80 ml. of acetone and 1.7 g. (0.013 mol.) of methylmercaptopacetyl chloride in 25 ml. of acetone. The acidified (pH 3.5) aqueous solution was extracted with ethyl acetate then concentrated in vacuo to yield, upon cooling, 7-methylmercaptopacetamido-3-(4-methyl-1,2,4-triazol-3-ylthiomethyl)- Δ^3 -cephem-4-carboxylic acid. The acid was dissolved in methanol, the solution was filtered, and a 5 percent solution of sodium methoxide in methanol was added to pH 6.8. Addition of ether to this solution caused precipitation of the sodium salt which was collected and recrystallized from methanol-ether to give 0.62g. of pure material.

- 7-amino-3-(4-allyl-1,2,4-triazol-3-ylthiomethyl)- Δ^3 -cephem-4-carboxylic acid

7-amino-3-(1,2,3-triazol-4-ylthiomethyl)- Δ^3 -cephem-4-carboxylic acid
 7-amino-3-(3-methyl-1,2,3-triazol-4-ylthiomethyl)- Δ^3 -cephem-4-carboxylic acid
 7-amino-3-(5-methyl-1,2,3-triazol-4-ylthiomethyl)- Δ^3 -cephem-4-carboxylic acid
 7-amino-3-(3,5-dimethyl-1,2,3-triazol-4-ylthiomethyl)- Δ^3 -cephem-4-carboxylic acid
 7-amino-3-(3-ethyl-1,2,3-triazol-4-ylthiomethyl)- Δ^3 -cephem-4-carboxylic acid
 7-amino-3-(5-ethyl-1,2,3-triazol-4-ylthiomethyl)- Δ^3 -cephem-4-carboxylic acid
 7-amino-3-(3,5-diethyl-1,2,3-triazol-4-ylthiomethyl)- Δ^3 -cephem-4-carboxylic acid
 7-amino-3-(3-methoxymethyl-1,2,3-triazol-4-ylthiomethyl)- Δ^3 -cephem-4-carboxylic acid
 7-amino-3-(4-pyridylthiomethyl)- Δ^3 -cephem-4-carboxylic acid
 7-amino-3-(3-pyridylthiomethyl)- Δ^3 -cephem-4-carboxylic acid
 7-amino-3-(4-pyrimidylthiomethyl)- Δ^3 -cephem-4-carboxylic acid
 7-amino-3-(2-pyrazinylthiomethyl)- Δ^3 -cephem-4-carboxylic acid.

EXAMPLE 8

When the procedure of Example 2 is followed using a 7-amino-3-heterocyclithiomethylcephalosporin listed in Example 7, the corresponding 7-methylmercaptoacetamido-3-heterocyclithiomethyl- Δ^3 -cephem-4-carboxylic acid is obtained.

EXAMPLE 9

When the procedure of Example 3 is followed using a 7-amino-3-heterocyclithiomethylcephalosporin listed in Example 7, the corresponding 7-ethylmercaptoacetamido-3-heterocyclithiomethyl- Δ^3 -cephem-4-carboxylic acid is obtained.

EXAMPLE 10

When the procedure of Example 4 is followed using a 7-amino-3-heterocyclithiomethylcephalosporin listed in Example 7, the corresponding 7-n-propylmercaptoacetamido-3-heterocyclithiomethyl- Δ^3 -cephem-4-carboxylic acid is obtained.

EXAMPLE 11

An injectable pharmaceutical composition is formed by adding sterile water or sterile saline solution (2 ml.)

5 to 500 mg. of 7-methylmercaptoacetamido-3-(1-methyl-1,2,3,4-tetrazol-5-ylthiomethyl)- Δ^3 -cephem-4-carboxylic acid, sodium salt.

Pharmaceutical compositions of the other antibacterial compounds disclosed above may be formulated in a similar manner.

What is claimed is:

1. A compound of the formula:

in which:

R is lower alkyl of one to six carbon atoms;

M is hydrogen or an alkali metal or ammonium cation; and

A is CH_2SHet , where Het is a five or six membered heterocyclic ring containing two to four atoms selected from the group consisting of N, O and S, unsubstituted or substituted with from one to two groups selected from lower alkyl, alkoxyalkyl or trifluoromethyl, each alkyl or alkoxy having from one to four carbon atoms.

2. A compound as claimed in claim 1 where R is methyl, ethyl or propyl.

3. A compound as claimed in claim 2 where Het is triazolyl, tetrazolyl, oxazolyl, oxadiazolyl, thiazolyl or thiadiazolyl unsubstituted or substituted with one or two alkyl groups of one to four carbon atoms.

4. A compound as claimed in claim 3 being the compound 7-methylmercaptoacetamido-3-(1-methyl-1,2,3,4-tetrazol-5-ylthiomethyl)- Δ^3 -cephem-4-carboxylic acid.

5. A compound as claimed in claim 3 being the compound 7-ethylmercaptoacetamido-3-(1-methyl-1,2,3,4-tetrazol-5-ylthiomethyl)- Δ^3 -cephem-4-carboxylic acid.

6. A compound as claimed in claim 3 being the compound 7-n-propylmercaptoacetamido-3-(1-methyl-1,2,3,4-tetrazol-5-ylthiomethyl)- Δ^3 -cephem-4-carboxylic acid.

7. A compound as claimed in claim 3 being the compound 7-methylmercaptoacetamido-3-(4-methyl-1,2,4-triazol-5-ylthiomethyl)- Δ^3 -cephem-4-carboxylic acid.
